Primary Examiner — Darlington Ly**CLAIM**

The ornamental design for a fairing for a motorcycle, as shown and described.

DESCRIPTION

FIG. 1 is a front elevational view of a fairing for a motorcycle showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front and left side perspective view thereof; and, FIG. 8 is a rear and right side perspective view thereof.

The dark-gray contrasted showing of the fairing for a motorcycle represents the claimed design.

The light-gray contrasted or ghosted showing of the motorcycle portions are provided for the purpose of illustrating environmental structure and forms no part of the claimed design.
